United States Patent Office.

PRIMUS EMERSON, OF CARONDELET, MISSOURI.

Letters Patent No. 95,333, dated September 28, 1869.

IMPROVEMENT IN FEATHERING PADDLE-WHEELS.

The Schedule referred to in these Letters Patent and making part of the same.

To all whom it may concern:

Be it known that I, PRIMUS EMERSON, of Carondelet, in the county of St. Louis, and State of Missouri, have made certain new and useful Improvements in Feathering Paddle-Wheels; and I do hereby declare the following to be a full and true description thereof, referring to the accompanying drawings, and to the letters of reference marked thereon.

This invention relates to wheels, with paddles arranged movably in such wise that said paddles shall remain, during their motion, in a vertical, or very nearly vertical position, to prevent the same from lifting up bodies of water or from striking the water without acting fully and fairly to propel or otherwise give a useful effect.

The nature of this invention is, first, in the manner of feathering the paddles and of supporting the same, to allow for the movement required for feathering, and secondly, in the manner of relieving the eccentric ring, which herein acts to cause the feathering of the paddles, of friction to a great extent.

To enable those herein skilled to make and use my said improved paddle-wheel, I will now more fully describe the same, referring to the accompanying

Figure 1 as a side view; to

Figure 2 as a plan; and to

Figure 3 as a sectional view, showing the manner of supporting the paddles in the wheel-rim.

I support the wheel in the usual manner by its axle A, in proper bearings, *a*, upon the usual frame.

Connected firmly to the axle, by suitable spider castings or other means, I arrange the wheel-arms B, which support the wheel-rims C, the parts being secured by bolts or rivets in any manner desirable, and being formed of iron or wood.

In the rims C, (of which there may be two or more,) I arrange the paddles D, made of iron or wood.

Said paddles are arranged between the semicircular segments E, usually made of cast-iron, and the paddles are secured, by proper bolts passing through the central diametrical flanges of the segments E.

These segments form a narrow cylinder, which turns freely in the wheel-rim C, being guided laterally by flanges or side-plates *e*, which are secured to the wheel-rims.

To said segments, I connect the journals *e*, all of which are, at their outer ends, connected with the eccentric ring F.

This ring has a series of radial arms, *f*, connecting with the inner ring F'.

The parts F, *f*, and F' are thus joined to form a united body.

In order to support the body thus formed, and allow the same to rotate, I arrange, eccentrically, to the shaft A, the centre bearing G, supported by proper brace-bars, *g*, to the wheel-frame.

Said bearing has the rollers *h* on its outer circumference, and, to properly support the journals of said

rollers, said bearing will usually have circular flanges, H, generally as indicated in fig. 1.

The flanges H may revolve with the rollers *h* about the centre of the bearing-piece G, or the rollers *h* may simply rotate about their own journals, which will then be firmly secured to the bearing aforesaid.

In the revolution of the wheel thus formed the rims C, and the paddles therein, revolve about the axis of the shaft C, and as the ring F revolves about the axis of the bearing G, it is plain that by the connection of the paddles with said ring F, these will be moved, relatively, to the wheel-rims C, in accordance with the eccentricity of the ring F, the effect of which is to turn the paddles D and their segments E, in the wheel-ring, and to preserve the vertical position (or any other position originally intended) of the paddles during the full revolution thereof, said effect being achieved whether the journals *e* are at the upper edges of the segments E or at the lower edges thereof.

During this feathering-movement of the paddles, the segments E turn in their housings, in the wheel-rims C, but are always firmly guided and supported on all points of the circumference, thus resisting effectually strains and contusion, whether arising from the currents of water or from drift-wood, ice, or other obstructions.

By attaching the journals *e* at the upper edges of the segments E, it is apparent that the feathering-movement of the paddles is in the direction of the water-pressure, as produced by the current made by the wheel, and the feathering-movement thus requires little power of machinery for its accomplishment; but by the arrangement of the roller centre at G H *h*, the power required in actuating the eccentric ring F is reduced to a minimum, especially as nearly all friction is located centrally.

The paddles D may extend beyond the wheel-rims C, outside thereof some distance, the support, as given by the devices here described, to said paddles being sufficient to allow for such extension with proper safety.

The arrangement and construction of feathering paddle-wheel thus described, recommends itself by its simplicity of form, avoiding the use of projecting-cranks for feathering, and generally having its detail features well protected against breakage by the usual obstructions, such as snags, drift-wood, and ice, attendant upon ordinary navigation.

Having thus fully described my invention,

What I claim, is—

1. The circular segments E, arranged to support the paddles D, and to allow the feathering thereof in the wheel-rims C, substantially as set forth.
2. The segments E, their journals *e*, and the eccentric F of F', when combined with the bearing G and rollers *h*, substantially as set forth.

Witnesses:

PRIMUS EMERSON.
